Application May 13, 1954, Serial No. 429,489

10 Claims. (Cl. 242—25)

This invention relates to the handling of wire and the like and, more particularly, to a machine for paying off and taking up wire on large reels.

It has generally been the practice to patent wire in strands by passing continuous lengths through a heat treating furnace. In this process wire is heated above its critical temperature and then cooled. Heretofore the wire has been taken up in the form of coils. Wire so treated may subsequently be subjected to conventional cold drawing operations. After patenting, the coils are cleaned by dipping in suitable cleaning and coating solutions. It will be apparent that the wire cannot be cleaned and coated while it is on a reel.

There is a practical limit in respect to the weight of coils of wire which can be handled, employing conventional procedures. Generally such coils do not exceed 1,000 pounds in weight.

I have found that considerably heavier amounts of wire may be expeditiously handled by the use of the machine of this invention. Instead of patenting, cleaning and coating the wire in coil form, as has been the practice in the past, the present machine enables the use of large reels for paying off the wire to be treated and for taking up treated wire. The reels may satisfactorily handle wire loads as great as 4,000 pounds of wire each, in sizes ranging from .135 inch to .090 inch in diameter.

The machine is adapted to support a plurality of reels, preferably three, each of which may be readily and independently mounted on the machine, utilized for paying off or taking up wire, and then removed from the machine. Initially, two of the reels are loaded with wire to be treated and the third reel is empty. Either of the loaded reels serves as the pay-off reel, while the empty reel serves as the take-up reel. The other loaded reel constitutes a reserve pay-off reel.

In operation one of the pay-off reels is placed in service and wire wound thereon is paid off by the machine, subjected to treatment and then taken up on the empty reel. The treatment may consist of successively heating the wire, cooling the wire, acid-cleaning the wire to remove scale, washing the wire and passing the wire through a coating bath. The treating steps take place subsequent to withdrawing the wire from the selected pay-off reel and prior to rewinding the wire on the take-up reel.

Upon depletion of the selected pay-off reel, the spare pay-off reel is placed in service, the free end of the wire of the spare reel being welded to that leaving the selected reel. This is accomplished without stopping the machine or interrupting treatment of the wire which would cause improper heating of the same. The depleted reel thus becomes available for use as the take-up reel when the original take-up reel has been filled with treated wire. When the take-up reel is filled, it is removed from the machine and replaced with a loaded reel of untreated wire.

One important feature of the invention is that the pay-off and take-up reels are disposed in convenient proximity to each other in the same machine. This facil-

tates handling of the reels and supervision of the operation of the machine.

Another feature is that only a single empty reel is mounted on the machine, it being unnecessary to supply any additional empty reels or to remove empty reels from the machine, regardless of the number of full reels that are handled by the machine. At such time as a reel of untreated wire is emptied, it is refilled with treated wire. Thus, each reel serves as a pay-off reel from which untreated wire is withdrawn and then as a take-up reel on which treated wire is wound.

The primary object of the invention is to provide a machine for economically handling large reels of wire or the like.

15 Another object of the invention is to provide a machine of the character indicated that is adapted to be operated continuously while permitting loaded reels of wire to be readily mounted thereon or removed therefrom, as required.

20 A further object of the invention is to provide a machine for simultaneously paying off and taking up wire on large reels, the parts of the machine being so constructed and arranged that the reels may be quickly and easily placed in or out of active service, without stopping the machine.

25 A still further object of the invention is to provide a wire-handling machine of the type indicated that is capable of performing its intended functions in a satisfactory and trouble-free manner.

30 The foregoing objects and other objects, together with the advantages of this invention, will be readily understood by persons skilled in the art, from the detailed description that follows, taken in conjunction with the accompanying drawings which, respectively, describe and illustrate a preferred embodiment of the invention.

35 In the drawings:

Fig. 1 is a view in front elevation of a machine constructed in accordance with the invention;

Fig. 2 is an enlarged view, taken along line 2—2 of Fig. 1;

Fig. 3 is an enlarged view in elevation, taken along line 3—3 of Fig. 1;

Fig. 4 is an enlarged view in elevation, taken along line 4—4 of Fig. 1, parts being broken away for better illustration;

Fig. 5 is an enlarged view, taken along line 5—5 of Fig. 1;

Fig. 6 is an enlarged view, taken along line 6—6 of Fig. 2; and

Fig. 7 is a view taken along line 7—7 of Fig. 4.

Referring now to the drawings, wherein like reference characters denote corresponding parts throughout the several views, the machine illustrated therein includes a support frame generally indicated by numeral 10. The base of the frame consists of a plurality of spaced parallel I beams 11 which carry pairs of spaced angle members 12, 13 and 14 and a pair of spaced channel members 15 and 16. The frame also comprises a first pair of upstanding channel posts 17 and 18 and a second pair of similar posts 20 and 21, which are somewhat shorter than posts 17 and 18. A stationary horizontal channel bar 22 is secured to the upper ends of posts 17 and 18 (Fig. 1).

Three equi-spaced brackets 23 are, as best shown in Figs. 1 and 3, affixed to channel bar 22 by bolts 24. Each of these brackets projects forwardly of the channel bar and carries at its free end a bolt 25, from which an arm 26 is pivotally suspended. Secured to the lower end of each arm 26 is a shaft 27 which is provided with a freely rotatable guide pulley. The guide pulleys are identified in the drawings by reference characters P1, P2 and P3.

The frame supports a horizontally reciprocable channel bar 30 which is positioned below stationary channel bar

22. This channel bar is slideable on rollers 31 and is maintained thereon by rollers 32. Channel bar 30 also carries three brackets 33, which are similar to but shorter than brackets 23. Brackets 33 are spaced apart and are secured to channel bar 30 by bolts 34, which extend through elongated slots 35 in that channel bar to permit of horizontal adjustment of the corresponding brackets. As in the case of the earlier described brackets, an arm 36 is pivotally suspended from the forward end of each bracket 33 and carries a shaft 37, on which is mounted a freely rotatable guide pulley. The guide pulleys suspended from channel bar 30 are identified by reference characters P4, P5 and P6. It may be stated here that guide pulleys P1, P2 and P3 serve as pay-off guides, while guide pulleys P4, P5 and P6 serve as take-up guides during operation of the machine.

Directly below pulleys P1, P2 and P3 are reels R1, R2 and R3, respectively. Reels R1 and R2 are wound with untreated wire W1, while reel R3 is partially loaded with treated wire W2.

The reels are preferably identical and are adapted to be removably supported for rotation about coincident horizontal axes by corresponding pairs of fluid actuated jacks J1, J2 and J3. The jacks are preferably identical. One of the jacks, namely J2, is shown in detail in Fig. 5 and includes a base 40 mounted on the frame base, an upstanding cylinder 41, a piston 42, vertically reciprocable in the cylinder, and a block 43, secured to the upper end of the piston. Affixed to block 43 are a saddle 44 and a pair of arms 45 that are pivotally connected at their ends remote from the block to a corresponding bolt 46. Each bolt 46 is carried by a U-shaped bracket 47 which is mounted on an angle bracket 48 that is secured to upstanding channel members 49 which are part of frame 10 (Figs. 2, 3 and 5). Arms 45 are notched in the region of the corresponding saddle. A conduit 50 transmits fluid under pressure for actuating each jack from a source not shown to the jack cylinder.

A spindle 51 is removably disposed in each reel and is adapted to be supported at its ends by the saddles of a corresponding pair of jacks. Each spindle is provided with an anti-friction bearing 52 and carries a coaxial gear 53. It will be apparent from an examination of the drawings, particularly Figs. 1, 2 and 5, that the jacks and associated devices are so constructed and arranged as to permit the reels to be readily and independently placed in or removed from the machine, as required.

The reels are adapted to be selectively rotated through the medium of a rotary drive shaft 55 and associated devices that will now be described. Drive shaft 55 is parallel to the axes of spindles 51 and is supported by channel members 49. Shaft 55 is provided with a plurality of clutches, namely clutches C1, C2 and C3, that are adapted to coact with other parts to impart rotation to reels R1, R2 and R3, respectively, in response to rotation of shaft 55. The clutches are likewise preferably identical and, as best shown in Figs. 2, 3 and 5, each comprises a first toothed member 56 and a second toothed member 57. Clutch member 56 is freely rotatable about shaft 55, but is restrained against axial movement with respect thereto. Clutch member 57, on the other hand, is coupled to shaft 55 by a key 58 (Fig. 5) which permits of axial movement only of this member with respect to the shaft. Clutch member 57 has an annular groove 59.

The clutches are adapted to be readily placed into and out of active service by a corresponding means 60 which will next be described, reference being had particularly to Figs. 1, 2, 5 and 6. Each means 60 includes an actuating lever 61 consisting of a horizontal portion 62 and an upwardly projecting portion 63 that terminates in a gripping knob 64. Each lever 61 is rockably supported by an angle member 65 carried by the frame (Fig. 5), angle bracket 48 and a plate 66, which is mounted on frame channels 49. Each means 60 also includes a pair of short links 67 and 68 and a relatively long link 69. Link 67 is affixed

to and rockable with lever 61 and is pivoted at 70 to link 68. Link 69 is pivoted at its lower end to link 68, as indicated at 71, and is pivoted intermediate its ends to plate 66, as indicated at 72. A roller 73 carried at the upper end of link 69 registers with annular groove 59, in clutch member 57.

When the parts are in the relative positions shown in Fig. 6, clutch member 57 is out of engagement with clutch member 56 and, as a consequence, clutch C2 is out of active service. This clutch may be placed in active service by swinging lever 61 to the left, as viewed in Fig. 6. This imparts a corresponding increment of counter-clockwise rotation to lever portion 62 and links 67 and 69, thereby causing roller 73 to move clutch member 57 to the left and into engagement with clutch member 56.

A sprocket wheel 74 is secured to and rotatable with each clutch member 56. This sprocket wheel is connected to a second sprocket wheel 75 by means of an endless chain 76. Sprocket wheel 75 is keyed or otherwise secured to a shaft 77, which is provided with a pinion 78 that meshes with spindle gear 53. Thus rotation of each sprocket wheel 74 effects rotation of a corresponding spindle gear and reel.

The clutches are equipped with identical brakes for providing suitable tension in the wire supplied by corresponding reels, as such wire is being payed off therefrom. Only the brakes for clutches C2 and C3 are shown in the drawings (Fig. 2) and are identified by reference characters B2 and B3, respectively. Each brake, as shown in Figs. 5 and 6, comprises a drum 80 rotatable with corresponding clutch member 56. The drum is engaged by a brake band 81 which is anchored at one end to frame plate 66 by a connector 82. The other end of the brake band is secured to a lever 83 by a connector 84. One end of lever 83 is pivoted at 85 to a frame post 86. A weight 97 is attached to the other end of lever 83 and is adjustable therealong to correspondingly vary the loading on the brake band.

Rotation is imparted to drive shaft 55 by an arrangement of devices that will now be described, reference being had to Figs. 2 and 3. Such devices comprise an electric motor 90 having a rotary drive shaft 91. The motor is connected to and actuates a fluid drive 92 by means of a variable speed V-belt drive consisting of a pulley 93 affixed to and rotatable with shaft 91, a pulley 94 affixed to input shaft 95 of the fluid drive, and an open V-belt 96, engaging these pulleys. The fluid drive is provided with an output shaft 97 that is connected to a speed reducer 100 by means of a second variable speed V-belt drive consisting of a pulley 101 rotatable with shaft 97, a pulley 102 connected to input shaft 103 of the speed reducer and an open V-belt 104 engaging pulleys 101 and 102. The speed reducer has an output shaft 105, which carries a sprocket wheel 106. This sprocket wheel imparts rotation to a sprocket wheel 107 and thence to shaft 55, which is connected to the latter sprocket wheel through the medium of an endless chain 108.

A pair of capstans 110 and 111 is mounted for rotation with parallel rotary shafts 112 and 113, respectively, that are supported by frame posts 20 and 21. The capstans are driven in unison, in response to rotation of shaft 112 by a chain drive which comprises a sprocket wheel 114 affixed to shaft 112, a sprocket wheel 115 affixed to shaft 113 and a continuous chain 116 engaging both of these sprocket wheels. An idler sprocket wheel 117 is rotatable about the axis of a stub-shaft 118 carried by frame member 21 and meshes with chain 116. This sprocket wheel serves to take up excess slack in the chain.

Referring next to Fig. 3, there is illustrated therein a means 120 for imparting rotation to shaft 112 and thence to capstans 110 and 111. Means 120 includes an electric motor 121 which is mounted on the frame in a position above and rearward of motor 90. Motor 121 has a

rotary shaft 122 which is connected to a speed reducer 123 by a variable speed V-belt drive, comprising a pulley 124 secured to shaft 122, a pulley 125 secured to input shaft 126 of the speed reducer and an open V-belt 127, engaging these pulleys. The speed reducer has an output shaft 128, which is coaxial with and connected to shaft 112 by a coupler 129.

Means 120 functions as a driving mechanism for moving untreated wire from a selected pay-off reel R1 over a corresponding pay-off guide pulley P1, thence through a treating zone (not shown) wherein the wire is patented or otherwise treated, and eventually moving the treated wire W2 to the discharge of capstan 111, whence it passes over a take-up guide pulley P6 onto the take-up reel R3.

The machine is equipped with a means that coacts with capstan 111 and the wire carried thereby, for creating sufficient friction between the wire and the capstan to effect proper movement of the wire when there is no tension in the wire as it leaves that capstan. This means, as best shown in Figs. 1 and 3, comprises a feed roller 130, the peripheral portion of which is made of rubber or other suitable material for creating desired friction. The feed roller is rotatable about the axis of a shaft 131 which is parallel to capstan shaft 113. Shaft 131 is carried by arms 132 of a bracket 133, which is horizontally mounted for pivotal movement on a rod 134 that is carried by post 21. A lever 135 is pivoted to post 21, as indicated at 136, and is pivoted to a link 137, as indicated at 138. Shaft 131 is also pivoted to link 137. Lever 135 coacts with link 137 to raise or lower the feed roller with respect to capstan 111.

As was stated earlier herein, channel bar 30 is horizontally reciprocable relative to the frame. This bar is in the nature of a "fleeting" bar which cooperates with a selected take-up pulley P4, P5 or P6, to effect proper winding of treated wire on the corresponding take-up reel. Bar 30 is reciprocated on rollers 31 in response to rotation of drive shaft 55 by a mechanism 140, best shown in Figs. 1, 4 and 7. This mechanism includes an oscillatable lever 141 that is pivotal about a pin 142 carried by post 17. Lever 141 has an elongated slot 143 at its upper end, in which is disposed bolt 144 for adjusting the length of stroke of the bar. A sectional connecting rod 145 having a turnbuckle 146 for varying its effective length, is pivoted at one end to bolt 144 and, at its other end, to bar 30, as indicated at 147. A link 148 (Figs. 4 and 7) is pivoted at 149 to the lower end of lever 141 and at 150 to a reciprocable plate 151, which is mounted for horizontal sliding movement in a stationary guide plate 152, that is supported by the frame. Plate 151 carries a pair of parallel spaced rollers 153.

A cam 155 is located at all times between rollers 153 and is eccentrically mounted at an end of a rotary cam shaft 156 which is supported by frame posts 157 (Fig. 4). The cam shaft is provided with a worm wheel 158 that meshes with a worm 159, which is affixed to a shaft 160. Also affixed to shaft 160 is a sprocket wheel 161 that is connected to drive shaft 55 by a sprocket pinion 162 and an endless chain 163.

It will be evident from an examination of the drawings that rotation of drive shaft 55 effects corresponding rotation of sprocket wheels 162 and 161, worm 159, worm gear 158, cam shaft 156 and cam 155, in the order named. This causes reciprocation of plate 151, oscillation of lever 141 and reciprocation of bar 30 and its pulleys P4, P5 and P6, in timed relation to rotation of drive shaft 55 and the reel which serves as the take-up reel, namely R3, in the illustrated arrangement.

For the purpose of briefly describing the operation of the machine, it is assumed that the parts are in the relative position shown in the drawings and that motors 90 and 121 are in active service. Reel R1 constitutes the pay-off reel and untreated wire W1 is being payed off

therefrom, passing over corresponding pay-off pulley P1. Reel R2 is loaded with untreated wire W1 and serves as a spare. Reel R3 is the take-up reel onto which the treated wire W2 is wound, through coaction of the parts earlier described. It will be noted that clutch C3, corresponding to reel R3, is the only clutch in active service.

The reels are preferably of the same size. When reel R1 becomes depleted, reel R3 is filled with treated wire. As soon as reel R1 is emptied, the free end of the wire on reel R2 is passed over pulley P2 and is welded to the end of the wire leaving reel R1. Now reel R2 serves as the active pay-off reel. When reel R3 becomes fully loaded, treated wire W2 is cut at a point intermediate capstan 111 and take-up pulley P6, is passed over and into engagement with pulley P4 and is joined to reel R1, which now serves as the take-up reel. The loaded reel R3 is then removed from the machine and replaced with a full reel of untreated wire.

From the foregoing, it is believed that the construction, operation and advantages of my present invention will be readily comprehended by persons skilled in the art. It is to be clearly understood, however, that various changes in the machine set forth above may be made without departing from the scope of the invention, it being intended that all matter contained in the description or shown in the drawings shall be interpreted as illustrative only and not in a limiting sense.

I claim:

1. In a machine for handling wire or the like, first means adapted to support a plurality of reels for rotation about horizontal axes, a rotary drive shaft, second means for imparting rotation to the drive shaft, third means for effecting rotation of a selected reel in response to rotation of the drive shaft, the selected reel serving as a wire take-up reel and another of the reels serving as a wire pay-off reel, and fourth means for moving wire along a predetermined path from the pay-off reel to the take-up reel and for maintaining the wire under tension in the course of such movement, said fourth means including a variable speed drive independent of the drive shaft for imparting wire pay-off rotation to the pay-off reel.

2. In a machine for handling wire or the like, first means adapted to support a plurality of reels for rotation about horizontal axes, a rotary drive shaft, second means for imparting rotation to the drive shaft, third means for effecting rotation of a selected reel in response to rotation of the drive shaft, the selected reel serving as a wire take-up reel and another of the reels serving as a wire pay-off reel, a pay-off guide and a take-up guide spaced vertically from each reel, and fourth means independent of the drive shaft for imparting wire pay-off rotation to the pay-off reel, for moving the wire along a predetermined path from the pay-off reel to the take-up reel, and for maintaining the wire under tension in the course of such movement, the wire during such movement engaging the pay-off guide and the take-up guide corresponding, respectively, to the pay-off reel and the take-up reel.

3. In a machine for handling wire or the like, first means adapted to support a plurality of reels for rotation about horizontal axes, a rotary drive shaft, second means for imparting rotation to the drive shaft, third means for effecting rotation of a selected reel in response to rotation of the drive shaft, the selected reel serving as a wire take-up reel and another of the reels serving as a wire pay-off reel, a pay-off guide and a take-up guide disposed above each reel, said pay-off guides being stationary, said take-up guides being reciprocable along a path that is parallel to the axes of the reels, fourth means for imparting reciprocation to the take-up guides in response to rotation of the drive shaft, and fifth means independent of the drive shaft for imparting wire pay-off rotation to the pay-off reel, for moving the wire along a predetermined path from the

pay-off reel to the take-up reel, and for maintaining the wire under tension in the course of such movement, the wire during such movement engaging the pay-off guide and the take-up guide corresponding, respectively, to the pay-off reel and the take-up reel.

4. In a machine for handling wire or the like, first means adapted to support a plurality of reels for rotation about horizontal axes, a rotary drive shaft, second means for imparting rotation to the drive shaft, said second means including a variable speed drive, third means for effecting rotation of a selected reel in response to rotation of the drive shaft, the selected reel serving as a wire take-up reel and another of the reels serving as a wire pay-off reel, a pay-off guide and a take-up guide disposed above each reel, said pay-off guides being stationary, said take-up guides being reciprocable along a path that is parallel to the axes of the reels, fourth means for imparting reciprocation to the take-up guides in response to rotation of the drive shaft, and fifth means for imparting wire pay-off rotation to the pay-off reel, for moving the wire along a predetermined path from the pay-off reel to the take-up reel, and for maintaining the wire under tension in the course of such movement, the wire during such movement engaging the pay-off guide and the take-up guide corresponding, respectively, to the pay-off reel and the take-up reel.

5. In a machine for handling wire or the like, first means adapted to support a plurality of reels for rotation about horizontal axes, a rotary drive shaft, second means for imparting rotation to the drive shaft, third means for effecting rotation of a selected reel in response to rotation of the drive shaft, the selected reel serving as a wire take-up reel and another of the reels serving as a wire pay-off reel, a pay-off guide and a take-up guide disposed above each reel, said pay-off guides being stationary, said take-up guides being reciprocable along a path that is parallel to the axes of the reels, fourth means for imparting reciprocation to the take-up guides in response to rotation of the drive shaft, and fifth means for imparting wire pay-off rotation to the pay-off reel for moving the wire along a predetermined path from the pay-off reel to the take-up reel, and for maintaining the wire under tension in the course of such movement, the wire during such movement engaging the pay-off guide and the take-up guide corresponding, respectively, to the pay-off reel and the take-up reel, said fifth means including a variable speed drive.

6. In a machine for handling wire or the like, first means adapted to support a plurality of reels for rotation about horizontal axes, a brake for each reel, a rotary drive shaft, second means for imparting rotation to the drive shaft, third means for effecting rotation of a selected reel in response to rotation of the drive shaft and against the action of the corresponding brake, the selected reel serving as a wire take-up reel and another of the reels serving as a wire pay-off reel, and fourth means for imparting wire pay-off rotation to the pay-off reel against the action of the corresponding brake, for moving the wire along a predetermined path from the pay-off reel to the take-up reel, and for maintaining the wire under tension in the course of such movement.

7. In a machine for handling wire or the like, first means adapted to support a plurality of reels for independent rotation about coincident horizontal axes, a brake for each reel, a drive shaft disposed to one side of the reels and rotatable about an axis that is parallel to the axes thereof, second means for imparting rotation to the drive shaft, third means for effecting rotation of a selected reel in response to rotation of the drive shaft and against the action of the corresponding brake, the selected reel serving as a wire take-up reel and another of the reels serving as a wire pay-off reel, and fourth means for imparting wire pay-off rotation to the pay-off reel against the action of the corresponding brake, for moving the

wire along a predetermined path from the pay-off reel to the take-up reel, and for maintaining the wire under tension in the course of such movement.

5. In a machine for handling wire or the like, first means adapted to support a plurality of reels for rotation about horizontal axes, a brake for each reel, a rotary drive shaft, second means for imparting rotation to the drive shaft, third means for effecting rotation of a selected reel in response to rotation of the drive shaft and against the action of the corresponding brake, the selected reel serving as a wire take-up reel and another of the reels serving as a wire pay-off reel, a pay-off guide and a take-up guide disposed above each reel, said pay-off guides being stationary, said take-up guides being reciprocable along a path that is parallel to the axes of the reels, fourth means for imparting reciprocation to the take-up guides in response to rotation of the drive shaft, and fifth means for imparting wire pay-off rotation to the pay-off reel against the action of the corresponding brake, for moving the wire along a predetermined path from the pay-off reel to the take-up reel, and for maintaining the wire under tension in the course of such movement, the wire during such movement engaging the pay-off guide and the take-up guide corresponding, respectively, to the pay-off reel and the take-up reel.

9. In a machine for handling wire or the like, first means adapted to support a plurality of reels for rotation, a rotary drive shaft, second means for imparting rotation to the drive shaft, third means for effecting rotation of a selected reel in response to rotation of the drive shaft, the selected reel serving as a wire take-up reel, another of the reels having a supply of wire and serving as a wire pay-off reel and still another reel having a supply of wire and constituting a reserve reel, and fourth means independent of the drive shaft for moving wire along a predetermined path from the pay-off reel to take-up reel regardless of whether the take-up reel is temporarily disconnected from the wire being paid off by the pay-off reel, and fifth means for maintaining the wire under tension in the course of its movement from the pay-off reel to the take-up reel, the reserve reel and the pay-off reel being adapted, upon depletion of wire from the pay-off reel, to serve as the pay-off reel and the take-up reel, respectively.

10. In a machine for handling wire or the like, first means adapted to support a plurality of reels for rotation, a rotary drive shaft, second means for imparting rotation to the drive shaft, said second means including a variable speed drive, third means for effecting rotation of a selected reel in response to rotation of the drive shaft, the selected reel serving as a wire take-up reel, another of the reels having a supply of wire and serving as a wire pay-off reel and still another reel having a supply of wire and constituting a reserve reel, and fourth means independent of the drive shaft for moving wire along a predetermined path from the pay-off reel to the take-up reel and for maintaining the wire under tension in the course of such movement, said fourth means including a variable speed drive for imparting wire pay-off rotation to the pay-off reel, the reserve reel and the pay-off reel being adapted, upon depletion of wire from the pay-off reel, to serve as the pay-off reel and the take-up reel, respectively.
